(57) **CLAIM**

The ornamental design for a abdominal muscle training apparatus, as shown and described.

DESCRIPTION

FIG. 1 is a perspective view of an abdominal muscle training apparatus, showing my new design in a bent state;

FIG. 2 is a front elevation view thereof, in a flattened state;

FIG. 3 is a rear elevation view thereof, in a flattened state;

FIG. 4 is a left side elevation view thereof, in a flattened state; and,

FIG. 5 is a right side elevation view thereof, in a flattened state.

The indicia or broken lines shown on the figures are for illustrative purposes only and are hereby disclaimed as forming no part of Applicant's claimed invention.
